UNITED STATES PATENT OFFICE.

NICK SIGNORELLI, OF AMELIA, LOUISIANA.

HARNESS-BUCKLE.

1,005,341.

Specification of Letters Patent. Patented Oct. 10, 1911.

Application filed April 29, 1911. Serial No. 624,161.

To all whom it may concern:

Be it known that I, NICK SIGNORELLI, a citizen of the United States, residing at Amelia, in the parish of St. Mary and State 5 of Louisiana, have invented a new and useful Harness-Buckle; and I do hereby declare the following to be a full, clear, and exact description of the invention, such as will enable others skilled in the art to which it 10 appertains to make and use the same.

This invention relates to a new and useful buckle, and more particularly to back-band or harness buckles.

The object of the invention is to produce 15 a buckle which is simple in construction and which may be locked and unlocked readily.

A further object of the invention is to provide a buckle for back-bands including means for taking up the slack in chain 20 traces, said means being provided with means for locking the buckle at the proper desired location on the back band.

In the drawings, there is only disclosed one form of the present invention, but in 25 practical fields, this form may require alterations, to which the applicant is entitled, provided the alterations may be made within the scope of what is claimed.

The invention comprises further features 30 and combination of parts, as hereinafter set forth, shown in the drawings and claimed.

In the drawings:—Figure 1 is a view in perspective, showing the application of the improved buckle as applied to a back band. 35 Fig. 2 is a sectional view on line 2—2 of Fig. 1. Fig. 3 is a sectional view on line 3—3 of Fig. 1.

Referring more particularly to the drawings, 1 designates the base plate of the buckle, which may be made of any suitable metal and by any suitable method. In the present application it is to be understood, that this base plate, is stamped from sheet metal. The rear face of the base plate is 40 provided with a depression 2 to receive the back band which passes through the buckle. Secured on the face of the base plate by means of the rivets 3 is an additional plate 4, through openings 5 and 6 of which and

the openings 7 and 8 of the plate 1, the back 50 band 9 passes. The plate 4 terminates at its lower portion at each side thereof into upwardly turned hooks 10 having openings 11, while the upper portion of the plate 4 is provided with oppositely arranged outstanding 55 ears 12 having apertures 13. An oscillating plate 14 is pivoted in the apertures of the ears, and is provided with a serrated edge 15 to engage the back band so as to hold the buckle in place thereon. The serrated edge 60 binds the back band between it and the bars 16. The oscillating plate 14 is provided with downwardly extending portions 17 which terminate into right angled extensions 18, which pass through the openings 65 11 of the hooks 10, there being suitable means 19 to prevent accidental withdrawal of the right angled portions of the plate 14. To withdraw the right angled portions of the plate 14 a slight downward pressure 70 should be applied on the hooks 10, so that when an upper pressure is applied on the plate 14, the right angled extending portions will be free to be drawn through the opening 11. 75

The object in providing the right angled extending portions is to provide means to prevent the accidental displacement of the chain and trace, two links 22 of which are in engagement with the hooks 10, thus making 80 a loop in the trace, in order to take up the slack therein.

It will be observed that the plate 14 is provided with means, serving simultaneously for holding the chain locked in position and the buckle locked on the back-band. 85

The invention having been set forth, what is claimed as new and useful, is:—

In combination, a base member consisting of two riveted plates having openings to receive a back-band, one of said plates terminating into upwardly extending hooks having openings, said hooks adapted to engage through two links of a chain trace for shortening the same, ears projecting outwardly 90 from one of the plates, an oscillating plate pivoted in the ears and provided with a serrated edge to engage the back-band, said 95

oscillating plate having right angled free portions to extend through the openings of the hooks, said right angled free portions having means to abut the hooks to prevent accidental displacement of the right angled portions through the openings.

In testimony whereof I have signed my

name to this specification in the presence of two subscribing witnesses.

NICK SIGNORELLI.
